UNITED STATES PATENT OFFICE.

MARTIUS K. SWARTZ, OF NISSWA, MINNESOTA.

EGG-CARRIER.

1,138,514.

Specification of Letters Patent.

Patented May 4, 1915.

Application filed December 19, 1913. Serial No. 807,644.

To all whom it may concern:

Be it known that I, MARTIUS K. SWARTZ, a citizen of the United States, residing at Nisswa, in the county of Crow Wing and 5 State of Minnesota, have invented certain new and useful Improvements in Egg-Carriers, of which the following is a specification.

My invention relates to egg carriers, and 10 has for its object to provide a carrier for eggs which will be suitable for use in transportation through the mails, and will be of such construction that the same may be used over and over again and rendered sanitary 15 and antiseptic at each use thereof.

The full objects and advantages of my invention will appear in connection with the detailed description thereof and are particularly pointed out in the claims.

20 In the drawings, illustrating the application of my invention in one form,—Figure 1 is a sectional end elevation of my carrier showing the same when placed in the shipping carton and when embodying eggs properly held in position. Fig. 2 is a plan view of the shipping crate with the parts extended. Fig. 3 is a side view of the same. Fig. 4 is an end view of the crate with the parts extended similar to Fig. 2.

25 As shown, the crate comprises a pair of rectangular wire outer frames 10 and 11 and a pair of similar inner or top frames 12 and 13 secured in proper spaced relation by wires 14 and 15, respectively, the top frames 12 and 13 being hinged together at 16, preferably by means of a loop of one of the spacing wires 14, as shown in Fig. 1.

The side wires of the outer frames 10 and 11 are connected by a series of transverse wires 17 and 18 in the same planes as the frames 10 and 11. The number of these transverse wires is shown to be six but obviously a greater or less number may be employed, as required. To each of the wires 40 17 are secured the lower ends 19 of spiral springs 20. In the form shown, two of such spiral springs are illustrated connected with each of wires 17, making a dozen in all, which is a convenient and practicable form 45 of the device. The other ends of the spiral springs 20 will preferably be secured to a central wire 21 extending longitudinally of the top frame 12. Similarly to each of the wires 18 are secured the lower ends 22 of

55 spiral springs 23 having their other ends secured to a central wire 24 in the plane of the top frame 13. When the respective frames are folded together on the hinged portion, the spiral springs 20 and 23, respectively, on each frame will come one above the other 60 with the open tops in juxtaposition.

The respective spiral springs are so shaped as to form a space within the same when in juxtaposition for the reception of a single egg. Since the eggs are more pointed at 65 one end than the other it is practicable to make the springs for the reception of the pointed end of the egg somewhat different in shape than the springs for the reception of the larger end of the egg, but I do not 70 wish to limit myself to any particular shape of the coöperating springs other than that which will receive and hold an egg when the springs are in juxtaposed position after the 75 closing of the frames.

As indicated in Fig. 4, the eggs will first be placed within one of the sets of springs, as 20, with the ends of the eggs all pointing in the same direction. The other frame member 11, 13 will then be swung over on 80 its hinges bringing the springs 23 over the parts of the eggs protruding from springs 20, as indicated in Fig. 1. In the form shown this will inclose a dozen eggs, and each egg will be separately and yieldingly 85 held, and yet held so that no substantial shock can be transmitted to any portion of the egg. The crate may then be inclosed in a carton 25, as indicated in Fig. 1, which 90 carton may be of heavy fiberboard, pasteboard, wood, tin, or any other suitable material. The carton obviously can be made to receive one or more of the complete egg crates, as desired. When so cartoned the eggs may be sent through the mail by parcels 95 post with perfect safety.

The advantages of my egg carrying device will be apparent. By its use it will be practicable for a consumer in the city to obtain fresh eggs direct from the producer 100 in the country, said eggs being transported by parcels post in the carriers of my invention without danger of breakage. The outer carton 25 is no part of the carrier proper, and will, of course, be inexpensive and can 105 be thrown away after use. The wire carrier, however, will be returned and used over and over again, the same being perfectly sani-

tary as it may be thoroughly disinfected by being boiled or treated with antiseptic liquids after each use.

I claim:

- 5 1. A carrier for eggs comprising a pair of frames each consisting of two rectangular wire members held in spaced relation by wire uprights, said frames being hingedly connected together in the planes of the inner of said rectangular members, the outer of said rectangular members being provided with a plurality of cross wires, spiral springs having the end adjacent the smallest coil connected to said cross wires and the end adjacent the largest coil to a wire in the plane of the junction of the sections when the same are folded, the juxtaposed coils of corresponding pairs of said spiral springs being then positioned to receive and engage 10 15 20 the walls of an egg.

Copies of this patent may be obtained for five cents each, by addressing the "Commissioner of Patents, Washington, D. C."

2. A carrier for eggs comprising a pair of wire frame sections hingedly connected to fold together and formed so that when so folded a box-like frame structure is provided, spiral springs within each of said sections connected adjacent the smallest coil to the outside of the section and at the end of the largest coil to a wire in the plane of the junction of the sections when the same are folded, the juxtaposed coils of corresponding pairs of said spiral springs being then positioned to receive and engage the walls of an egg.

In testimony whereof I affix my signature in presence of two witnesses.

MARTIUS K. SWARTZ.
